(57) **CLAIM**

The ornamental design for a fishing reel, as shown and described.

DESCRIPTION

FIG. 1 is a front, left and top perspective view of a fishing reel showing our new design;

FIG. 2. is a front view thereof;

FIG. 3. is a rear view thereof;

FIG. 4. is a left side view thereof; and,

FIG. 5. is a top plan view thereof.

The broken lines shown represent unclaimed subject matter of the fishing reel and form no part of the claimed design.
